Attorney—Cyrus D. Samuelson et al.

[73] Assignee: **Penn Products Corporation, Randolph, Mass.**

[57] ABSTRACT

[22] Filed: **Dec. 7, 1972**

A calendar construction in which a lobed, resiliently flexible calendar-bearing annular disk is mounted for rotation upon a pedestal-supported drum and retained on the drum by a radially narrow lip which enables selective removal and replacement of the disk by forcing the disk over the lip. The disk may be indexed to a selected position where a portion of the calendar is at a predetermined viewing location, and abutments engage a lobe to retain the disk at that position. A relatively large display surface is provided at the viewable end of the drum for displaying advertising copy, other information or decorative effects.

CALENDAR DISPLAY CONSTRUCTION WITH INDEXING CALENDAR BEARING MEMBER

The present invention relates generally to calendars and pertains, more specifically, to calendars of the type having a readily replaceable calendar-bearing member carried by a calendar frame which is aesthetically pleasing and is especially well suited to displaying advertising copy, other information or decorative effects.

Calendars, and especially calendar stands and holders, have become popular as advertising premiums which are distributed by individuals, firms or companies and the like to customers and friends. These calendar stands and holders, aside from carrying calendars, often serve as vehicles for advertising literature. Since it is the invention of the distributor of such calendars to have the recipient display the calendar at a prominent location and keep the calendar for a long period of time, so that the distributor's advertising message is constantly before the recipient for the duration of that period, it would be advantageous to have available a calendar construction which is aesthetically pleasing and will bear calendar information which is easily kept up to date for a long period of time so as to encourage the recipient to keep the calendar.

It is therefore an important object of the invention to provide a calendar construction which is aesthetically pleasing and in which calendar information is easily and inexpensively kept up to date.

Another object of the invention is to provide a calendar construction which may be packaged in a compact, flat configuration for ease of mailing or distribution by other means and which readily may be erected for use.

Still another object of the invention is to provide a calendar construction of the type described above which is compact, yet carries legible long-term calendar information which is easily and inexpensively replaced for extending the term of the calendar information.

A further object of the invention is to provide a calendar construction having adequate, conspicuous display surfaces for carrying advertising copy, other information or decorative effects.

A still further object of the invention is to provide a calendar construction in which a calendar holder or stand is of unitary construction and which may be fabricated in large quantities at minimum expense.

The above objects, as well as still further objects and advantages, are attained by the invention which may be described as a calendar construction for displaying a selected calendar interval at a predetermined viewing location, the calendar construction comprising a frame, drum means projecting from the frame, a calendar-bearing member including an obverse surface extending in a direction transverse to the direction in which the drum means projects and carrying a plurality of calendar intervals thereon, the member having an aperture complementary to the drum means such that the member may be rotated selectively upon the drum means to index the member to a selected position for locating the selected calendar interval at the viewing location, and a lip integral with the drum means and extending laterally therefrom to overlap the calendar-bearing member along at least a portion of the perimeter of the aperture to retain the member upon the drum means between the frame and the top, the relative dimensions of the lip and the aperture and the relative

flexibility of the lip and the calendar-bearing member at the perimeter of the aperture being such that the member selectively may be forced over the lip to remove and replace the calendar-bearing member.

5 The invention will be more fully understood, while still further objects and advantages will become apparent, in the following description of an embodiment of the invention illustrated in the accompanying drawing, in which:

10 FIG. 1 is a front perspective view of a calendar constructed in accordance with the invention;

FIG. 2 is a front elevational view of the calendar with the calendar-bearing member separated from the calendar frame;

15 FIG. 3 is a side elevational view of the calendar of FIG. 2; and

FIG. 4 is a cross-sectional view taken along line 4—4 of FIG. 1.

Referring now to the drawing, and especially to FIG.

20 1 thereof, a calendar constructed in accordance with the invention is illustrated generally at 10. Calendar 10 is a desk calendar and has a frame 12 which includes a base 14 extending generally horizontally for supporting the frame upon a desk top (not shown), and a pedestal 16 extending upwardly with respect to the base 14

25 for supporting a calendar-bearing member shown in the form of a disk 20. Disk 20 includes an obverse surface 22 upon which there is printed, or otherwise inscribed, a plurality of calendar intervals 24. In this instance, each interval 24 comprises a month of a calendar year, and each consecutive month of the calendar year appears in sequence around the disk 20.

30 Turning now to FIGS. 2 through 4, as well as to FIG. 1, disk 20 has an annular configuration which includes an outer periphery 26 and an inner circular aperture 28. The pedestal 16 is provided with a drum means shown in the form of a drum 30 projecting generally perpendicular to the pedestal 16 and including a drum surface 32 having an outside diameter complementary

35 to the inside diameter of the aperture 28 of the disk 20 so that the disk may be journaled for rotation upon the drum 30 with the obverse surface 22 transverse to the drum 30. Disk 20 is lobed and, in this instance, includes six lobes 34 spaced equidistantly around the perimeter of the disk. Each lobe 34 carries a one-month calendar interval 24. As viewed in FIG. 1, the uppermost lobe 34a is located at a predetermined viewing location 36 while the lowermost lobe 34b is captured between

40 abutment means shown in the form of a pair of parallel abutments 38 projecting from the frame 12 generally parallel to the drum 30 and extending along the frame generally parallel to complementary edges 39 of the lowermost lobe 34b. In this manner, the current calendar month is located and retained at the predetermined viewing location 36.

45 Disk 20 is retained upon drum 30 by a relatively thin lip 40 extending laterally from the drum in a radial direction to overlap the disk along the perimeter of the aperture 28 so that the disk 20 is secured between the lip 40 and a boss 42 on the pedestal 16.

50 Disk 20 is retained upon drum 30 by a relatively thin lip 40 extending laterally from the drum in a radial direction to overlap the disk along the perimeter of the aperture 28 so that the disk 20 is secured between the lip 40 and a boss 42 on the pedestal 16.

55 Disk 20 is retained upon drum 30 by a relatively thin lip 40 extending laterally from the drum in a radial direction to overlap the disk along the perimeter of the aperture 28 so that the disk 20 is secured between the lip 40 and a boss 42 on the pedestal 16.

60 Disk 20 is fabricated of a resiliently flexible material such as, for example, Bristol board or a like paper stock. Other suitable materials, such as synthetic resins, will be apparent to those skilled in the art of materials. The resiliently flexible characteristic of the disk material enables the lowermost lobe 34b to be lifted manually from between the abutments 38 so that the disk 20

may be rotated upon the drum 30 to index the disk to another selected position for locating a selected calendar month at the viewing location 36. Since the months are located in consecutive clockwise sequence around the perimeter of the disk 20 the disk merely need be rotated through 60° of counterclockwise rotation to bring lobe 34c and the next consecutive month to the predetermined viewing location 36. Upon such rotation, the lobe 34d, which is next in sequence to the previously captured lowermost lobe 34b, will be deflected out of the plane of the disk 20 as the leading edge 39a of that lobe 34d engages a ramp surface 44 on the adjacent abutment 38 so that the next consecutive lobe 34d will ride over the adjacent abutment 38 and then drop back into the plane of the disk 20, once the lobe 34d is completely between the abutments 38, to capture the lobe 34d between the abutments 38 and secure the next selected uppermost lobe 34c at the predetermined viewing location 36.

As best seen in FIG. 4, the lip 40 extends radially only a short distance beyond the inner peripheral edge 46 of the aperture 28 of the disk 20 sufficient to retain the disk in place upon the surface 32 of the drum 30. However, the overlap is held to a minimum so that the flexible nature of the material of the disk 20 enables the disk to be removed from the drum 30 by pulling the disk in a direction parallel to the drum surface 32 to force the disk 20 over the lip 40 and off the drum 30. Likewise, the disk 20 may be placed on the drum 30 by pushing the disk over the lip 40 and onto the drum surface 32. The resiliently flexible nature of the material of the disk, coupled with the relative dimensions of the lip 40 and the aperture 28, enables selective removal and replacement of the disk with ease.

In the illustrated embodiment, the disk 20 carries one full calendar year and would be replaced each year. Six months of the year are printed upon the obverse surface 22, while the remaining 6 months of the year are printed on the reverse surface 48 of the disk 20 so that once during the year the disk is removed from the drum 30, reversed, and then replaced on the drum.

Drum 30 is provided with a relatively large diameter; that is, the outside diameter of the drum surface 32 is preferably of the order of magnitude of approximately one-half the overall outside diameter of the disk 20. The relatively large diameter of the drum 30 enables a display surface area 50 to be located on the frame in a relatively conspicuous location so that the display surface area, which is bounded essentially by the drum surface 32, may be viewed along with the obverse surface 22 of the disk 20. The relatively large display surface area 50 then can be provided with aesthetically appealing decorative effects, advertising copy or other information. Thus, the calendar construction of the invention provides not only a functional calendar which can be continuously up-dated for years to come, but provides, as well, a conspicuously located surface area for the display of advertising copy, general information, monograms, or decorative designs. The lobed configuration of the disk 20 adds to the aesthetic appeal of the overall calendar construction.

The frame 12 may be either stored or transported, such as by mail, in a flat configuration, as illustrated in FIGS. 2 and 3, and may then be erected for use as a desk top calendar as illustrated in FIGS. 1 and 4. The frame 12 is advantageously fabricated in a unitary structure of plastic material, one such material being

polypropylene. Other suitable plastic materials will become apparent to those skilled in the art of materials. The use of such materials as polypropylene enables the base 14 to be connected to the pedestal 16 by means of an integral plastic hinge 52 which includes thin sections 54 interconnecting the base 14 with the pedestal 16. These thin sections 54 permit the plastic to be bent or folded along the line defined by the thin sections. The base 14 is beveled along the surface 56 and the pedestal 16 is likewise beveled along a corresponding surface 58 so that the pedestal 16 may be pivoted from a first position, wherein the pedestal and the base lie flat and generally coextensive (as FIGS. 2 and 3), and a second position, wherein the pedestal is erect and projects vertically upwardly almost perpendicular to the first position (as seen in FIGS. 1 and 4). Projecting upwardly from the beveled surface 56 is a detent projection 60 which is located in a position to engage a detent shelf 62 running along a slot 64 in the corresponding surface 58 of the pedestal 16 to lock the pedestal in the erect position. Thus, the calendar may be packaged and mailed or otherwise shipped or distributed in a convenient flat configuration and is readily erected for use.

It will be apparent, from the FIGS. 2 through 4, that the calendar frame 12 is easily molded in one piece in a relatively simple mold and therefore can be fabricated in large numbers at an economically low cost.

Calendar 10 optionally may be used as a wall calendar rather than a desk top calendar. Thus, the pedestal 16 is provided with a recess 66 having a keyhole slot 68 contiguous with the rear surface 70 of the frame 12. The frame 12, in the flat configuration, thus may be hung upon a wall by a nail or other fastener (not shown) which will be anchored in the wall and will pass through the keyhole slot 68.

The base 14 is also provided with a display surface area 72 upon which may be placed advertising copy, other information or decorative effects and the like. Other types of bases may be employed where special calendar locations are desired. For example, a base of the type described in U.S. Pat. No. 3,469,336, may be utilized where a calendar constructed in accordance with the invention is to be attached to a telephone.

It is to be understood that the above identified description of an embodiment of the invention is provided by way of example only. Various details of design and construction can be modified without departing from the true spirit and scope of the invention as set forth in the appended claims.

The embodiments of the invention in which an exclusive property or privilege is claimed are defined as follows:

1. A calendar construction for displaying a selected calendar interval at a predetermined viewing location, said calendar construction comprising:

a frame;
a drum projecting from the frame;
a calendar-bearing member including an obverse surface extending in a direction transverse to the direction in which the drum projects and carrying a plurality of calendar intervals thereon, said member having an aperture complementary to the drum such that the member may be rotated selectively upon the drum to index the member to a selected position for locating the selected calendar interval at the viewing location; and

a lip integral with the drum and extending laterally therefrom to overlap the calendar-bearing member along at least a portion of the perimeter of the aperture to retain the member upon the drum between the frame and the lip; the relative dimensions of the lip and aperture and the relative flexibility of the lip and the calendar-bearing member at the perimeter of the aperture being such that the member selectively may be forced over the lip to remove and replace the calendar-bearing member; the calendar-bearing member and the frame include complementary means for retaining the calendar-bearing member in said selected position.

2. The invention of claim 1 wherein:

the drum includes a cylindrical drum surface projecting generally perpendicular to the frame and having a prescribed diameter;

the calendar-bearing member is an annular disk and the aperture is a circular aperture located centrally therein and having an inside diameter complementary to the diameter of the drum surface such that the disk is journaled upon the drum surface and the obverse surface extends generally perpendicular to the drum; and

the lip is circular, extends generally perpendicular to the drum surface and has a diameter only slightly larger than the diameter of the drum surface and the diameter of the circular aperture.

3. The invention of claim 2 wherein the disk includes a reverse surface carrying a plurality of calendar intervals such that the disk may be removed selectively, reversed and replaced for extended calendar use.

4. The invention of claim 2 wherein the disk is resiliently flexible along the perimeter of the aperture relative to the drum and the lip.

5. The invention of claim 2 including a display surface area on the frame, said area being bounded essentially by the drum surface and viewable along with the obverse surface of the disk, the diameter of the drum surface being great enough to enable said display surface area to carry a display of sufficient area for viewing.

6. The invention of claim 5 wherein the diameter of the drum surface is of the order of magnitude of approximately one-half the overall diameter of the disk.
7. The invention of claim 2 wherein the frame includes:
- a base; and
- a pedestal integral with the base for extending upwardly therefrom; and
- said drum projects from the pedestal generally perpendicular thereto.
8. The invention of claim 7 wherein the base and the pedestal are interconnected with hinge means permitting the pedestal to be pivoted from the upwardly extending position essentially into the same plane as the base.
9. The invention of claim 1 wherein said complementary means include:
- a plurality of lobes on said disk along the outside perimeter thereof; and
- complementary abutment means on the frame for engaging a lobe to retain the disk in the selected position.
10. The invention of claim 9 wherein:
- the abutment means include abutments integral with the frame and projecting therefrom generally parallel to the drum; and
- the lobes have opposite edges extending generally parallel to the abutments such that any one lobe can be located and captured between the abutments, the lobes being resiliently flexible in the direction parallel to the drum to enable the captured lobe to be released from between the abutments for rotation of the disk.
11. The invention of claim 9 wherein each lobe carries one calendar interval.
12. The invention of claim 11 wherein the disk includes a reverse surface carrying a plurality of calendar intervals such that the disk may be removed selectively, reversed and replaced for extended calendar use.
13. The invention of claim 12 wherein the disk has six lobes and each lobe carries a calendar interval of one month.
